United States Patent Office.

AMOS A. HOTCHKISS, OF HANNIBAL, MISSOURI, ASSIGNOR TO HIMSELF AND WILLIAM J. QUALEY, OF SAME PLACE.

Letters Patent No. 94,960, dated September 21, 1869.

IMPROVED BRAKE-SHOE.

The Schedule referred to in these Letters Patent and making part of the same.

To all whom it may concern:

Be it known that I, AMOS A. HOTCHKISS, of Hannibal, Marion county, State of Missouri, have invented a new and useful improved Brake-Shoe, of which the following is a full, clear, and exact description, reference being had to the annexed drawing, making a part of this specification, in which—

Figure 1 represents a longitudinal section of my shoe.

Figure 2 represents a plan of the back of same.

Similar letters indicate like parts.

The object of my invention is to make a brake-shoe, the sole of which may be attached without bolt or screw, may be readily adjusted, and, when worn out, replaced by a new one in an expeditious manner.

A, figs. 1, 2, represents the shoe;

B, fig. 1, the sole; and

C, figs. 1, 2, the opening in the shoe to receive the brake-beam.

The sole B is furnished with two dovetailed projections or lugs, d d', having shoulders, 1 2 3 4, as seen, the one being an exact counterpart of the other.

In the shoe are made two openings or recesses, h h', as seen, for the reception of these lugs, and h' has pivoted in it a catch, b, having a spring, o, which may be straight or spiral, as desired.

Over the inner end of the catch is an opening, g, figs. 1, 2, to insert a rod or other suitable instrument, in order to press back the catch.

The spring and catch are easily accessible through the opening c in the shoe, whenever necessary for repairs or other reason.

The sole is attached by inserting one lug in h, and then pressing the other against the catch, which, giving

way, allows it to pass, and immediately springs back, firmly locking the shoe by pressing the lugs against the sides of the recesses, as seen.

Should one end of the sole become more worn than the other, as is often the case, by simply pressing back the catch through the opening g, the sole may be removed, and, by reason of the exact similarity of the lugs, changed end for end in its shoe till, being completely worn out, another is substituted. This power of reversing the sole so as to obtain all the wear out of it of which it is susceptible, is one great advantage of my peculiar construction.

Another is the rapidity with which this change can be made, and the extreme simplicity of its construction, which almost precludes the possibility of its getting out of order.

I am aware that the soles of brake-shoes have been attached to their shoes by dovetailed projections, so as to dispense with bolts and screws, and therefore I do not claim, broadly, this construction; but

What I do claim as my invention, and desire to secure by Letters Patent, is—

1. The spring-catch b, working in a socket in the brake-shoe, for the purpose of holding the sole in place, constructed and operating substantially as herein described and shown.

2. The sole B, with its lugs, shoe A, spring o, and catch b, all arranged, constructed, and operating substantially as and for the purpose shown and specified.

AMOS A. HOTCHKISS.
